WILLIAM REDFORD MULOCK, OF WINNIPEG, MANITOBA, CANADA.

BELT.

Application filed May 17, 1926. Serial No. 109,762.

The invention relates to improvements in holding the free end of the buckled strap belts, particularly those utilized for holding up trousers and the like and an object of the invention is to provide a simple, inexpensive and effective belt construction which insures, upon the belt being put on and buckled in the ordinary way, that the trousers and the like are held at the desired height and are prevented from slipping and without having to resort to the use of loops or straps as customarily employed.

With the above more important object in view, the invention consists essentially in the arrangement and construction of parts hereinafter more particularly described, reference being had to the accompanying drawing, in which:

Fig. 1 is a perspective view of the belt.

Fig. 2 is an enlarged detail face view of the inner face of the belt.

Fig. 3 is an enlarged detailed sectional view at 3-3' Figure 2.

Fig. 4 is an enlarged detailed sectional view at 4-4' Figure 2.

25 In the drawing like characters of reference indicate corresponding parts in the several figures.

At the present time trousers or pants are usually held by a belt buckled around the body which belt runs through and is held in straps or loops firmly attached at the upper edge of the trouser waist band. With such arrangement, the trousers usually slip down until the belt engages at the hips. The result is not desirable as the trousers usually fall too low and sag at the crotch and also between the belt straps and further the position of the belt is not at a comfortable place.

The belt which I have invented overcomes the above objections and without requiring to resort to straps or loops and it insures that the trousers will fit neatly and comfortably and that the belt can be placed at the most comfortable position. The belt which I provide may be fastened in place by a tongued buckle or in any other well known manner.

In the present instance, the belt is shown as formed from an outer leather or such like strap 1, one end of which carries a buckle 2 having a tongue 3 and which is adapted to receive the other end of the strap in the manner shown and hold the same in any adjusted position around the trousers. The customary loops 4 and 5 are provided for

To the inner side of the strap 1, I have secured in any suitable manner an inner strip 6 which has the inner face thereof presenting gripping projections 7 adapted to engage the cloth of the trousers. The projections shown are arranged in intersecting oblique rows and present sharp biting edges 8. Each projection is wedge shaped in form and terminates in the biting edge 8. It will be observed that one end of the strip 6 is free to underlie the buckle and a loop 9 is provided to receive such end.

Whilst I have shown a single strip 6, it will be readily understood that the strip 6 could be made in sections which might cover only part of the inner face of the strap. The strip 6 is selected so that it will be flexible and will present a plurality of integrally formed independent gripping projections having a high co-efficient of friction. I have found that a rubber strip serves very effectively but obviously any other commodity having similar qualities will serve my purpose.

Whilst I have herein shown the strip 6 as attached such as by cementing to the strap 1, it will be understood that primarily in so far as my invention is concerned, it is only essential that the belt have integrally formed gripping projections on its inner face to engage and hold the trousers when the belt is applied thereon.

I am aware that belts having devices thereon which penetrate the cloth of the trousers have been used. These, however, are detrimental to the cloth as they cut, tear or deface it after they have been in use for a period of time. In my case, however, the projections do not penetrate the cloth but simply frictionally grip without penetrating and insure that there can be no slipping.

When one uses my belt, he pulls the trousers up to the most comfortable fitting position and when passing the belt around the waist, he locates it at the most comfortable position. Upon tightening up the belt and fastening it in the usual way, it will be found that the trousers will remain suspended in the desired position, the frictional gripping projections holding the trousers and preventing any down slipping thereof. I might point out that the end of the strip which underlies the buckle insures that the front of the trousers cannot sag down as obviously

would occur if such were not used to the rear of the buckle.

What I claim as my invention is:—

The combination with a belt strap provided with buckling means, of a flexible rubber strip cemented to the inner face of the belt strap and of the full width thereof and having the inner face provided with a plu-

rality of integrally formed wedge shaped gripping projections, the projections being arranged in intersecting diagonal rows crossing the face of the strip.

Signed at Winnipeg this 20th day of April, 1926.

WILLIAM REDFORD MULOCK.
